UNITED STATES PATENT OFFICE

127,826

DESIGN FOR AN ELECTRON TUBE

Eugene J. Hoffman, Emporium, Pa.

Application August 16, 1940, Serial No. 94,458

Term of patent 14 years

To all whom it may concern:

Be it known that I, Eugene J. Hoffman, a citizen of the United States of America and residing at 409 E. Third Street, Emporium, Pennsylvania, have invented a new, original, and ornamental Design for an Electron Tube, of which the following is a specification, reference being had to the accompanying drawing, forming a part thereof, in which:

Fig. 1 is a front elevational view of an electron tube showing my new design.

Fig. 2 is a side elevational view of Fig. 1.

Fig. 3 is a top end view of Fig. 1.

I claim:

The ornamental design for an electron tube, as shown.

EUGENE J. HOFFMAN.
